UNITED STATES PATENT OFFICE.

THEODORE SARLLS, OF SANDERS, KENTUCKY, ASSIGNOR OF FORTY-NINE PER CENT
TO THOMAS E. WELDON, OF SPARTA, KENTUCKY.

PUMPING APPARATUS FOR CISTERNS.

1,417,415.

Specification of Letters Patent. Patented May 23, 1922.

Application filed February 5, 1921. Serial No. 442,863.

To all whom it may concern:

Be it known that I, THEODORE SARLLS, a citizen of the United States, residing at Sanders, in the county of Carroll and State 5 of Kentucky, have invented certain new and useful Improvements in Pumping Apparatus for Cisterns, of which the following is a specification.

This invention relates to pumping devices 10 and has special reference to pumping apparatus for cisterns and other like reservoirs.

One important object of the invention is to improve and simplify the general construction of devices of this character.

A second important object of the invention is to provide an improved pumping device for cisterns wherein the discharge of water will be effected by compressed air so 20 that proper discharge may be obtained irrespective of the depth of the cistern.

A third important object of the invention is the provision of improved means for discharging water from a cistern wherein 25 the water to be discharged may be kept under air pressure so that the mere opening of a valve will permit water to be discharged.

With the above and other objects in view 30 as will be hereinafter apparent the invention consists in general of certain novel details of construction and combinations of parts hereinafter fully described, illustrated in the accompanying drawings, and specifically claimed.

The figure is a section through cistern showing the improved pumping apparatus in position.

In the embodiments of the invention here- 40 in illustrated there is disclosed a cistern or reservoir 10 of ordinary construction and provided with the usual lid or cover 11. Located within this cistern or reservoir and reaching from the bottom thereof to a point 45 near the top of the cistern is a discharge tank 12. This tank is closed at the top and is only open to the liquid 13 in the cistern at the bottom, an inwardly opening check valve 14 being provided at this point for 50 the purpose of allowing free flow of water into the cylinder 11 and of preventing water from flowing out of that cylinder. Located in convenient relation to the cistern is an air pump 15 of any preferred type, the 55 pump here shown being such as is usually

employed in pumping air into automobile tires. This pump is connected by flexible tubing 16 through a check valve 17 to a pipe line 18. The check valve 17 opens away from the pump so that any air forced into 60 the pipe line cannot flow back as the pump handle is lifted. Connected to the pipe line 18 is a pressure gage 19.

This pipe line 18 is continued down through the cistern and enters the cylinder 65 near the bottom at which point it terminates in an open end 24. Located on this pipe line is a three-way valve 25 to one outlet of which is connected a pipe 26 which is laid to any desired point at which it is 70 wished to draw off water, being there provided with a valve or babb 27.

In operation the three-way valve 25 is turned so that communication is established between the pump and the cylinder 12. In 75 this form it is also to be noted that a pipe 28 connects with the top of the cylinder being there fitted with a blow-off valve 29. In order to fill the cylinder the blow-off valve 29 is opened so that the water may 80 rise in the cylinder. Then the blow-off valve 29 is closed and the pump operated. This forces air into the bottom of the cylinder and this air will rise through the water to the top of the cylinder forming, 85 as in the other case, a cushion of compressed air. The three-way valve 25 is then turned to establish communication between the cylinder 12 and the pipe 26 thus cutting off communication with the pump 90 15. The apparatus is now ready to deliver water and by opening the babb 27 the water will flow out of it. It is readily understood that on proper manipulation of the valve 25 the pressure in the cylinder due to the 95 pump 15 may be increased at any time in the emptying of the cylinder and that the cylinder may be readily refilled by opening the valve 29.

There has thus been provided a simple 100 and efficient device of the kind described and for the purpose specified.

It is obvious that minor changes may be made in the form and construction of the invention without departing from the material principles thereof. It is not therefore desired to confine the invention to the exact form shown and described, but it is wished to include all such as properly come 105 within the scope claimed.

Having thus described the invention, what is claimed as new, is:—

The combination with a cistern or reservoir; of a vertical cylinder located within said cistern or reservoir and provided at 5 its lower end with a check valve opening inwardly to the cistern, an air pump, a pipe line connecting said air pump and the lower end of said cylinder, said pipe line includ-

ing a check valve opening away from said 10 pump and a three-way valve, a draw-off pipe connected to said three-way valve and provided with an outlet bibb, and a blow-off valve connected to the upper end of said cylinder.

In testimony whereof I affix my signature.

THEODORE SARLLS.
